UNITED STATES PATENT OFFICE.

GEORGE LIGOWSKY, OF CINCINNATI, OHIO, ASSIGNOR TO THE LIGOWSKY
CLAY PIGEON COMPANY, OF SAME PLACE.

FLYING TARGET.

SPECIFICATION forming part of Letters Patent No. 256,227, dated April 11, 1882.

Application filed February 21, 1882. (No model.)

To all whom it may concern:

Be it known that I, GEORGE LIGOWSKY, a citizen of the United States, residing at Cincinnati, in the county of Hamilton and State of Ohio, have invented certain new and useful Improvements in Flying Targets, of which the following is a specification.

The object of my invention is to construct a flying target or clay pigeon in such a manner as to insure the utmost stability of axial rotation when projected from a trap or sender, and cause the device to descend gradually, provided it is not destroyed by shot or other projectiles fired thereat. These results are accomplished by providing such targets or substitute birds with a concave body or shell, terminating at bottom with an inwardly-bent rim, which rim not only adds to the axial rotation of the device by increasing its peripheral weight, but also serves as a chamber or channel in which air is moderately compressed, as hereinafter more fully described, and pointed out in the claims.

My invention further consists in joining the concave body of the target to this inturned rim by an intermediate member having a reverse curve to said rim, as hereinafter more fully described, and pointed out in the claims.

In the annexed drawings, Figure 1 is a plan of my improved form of target or clay pigeon. Fig. 2 is an enlarged axial section of the same. The body A of the "target," "pigeon," or "bird," as it is variously termed, is concave in general contour, and is preferably composed of clay or earthenware or other material sufficiently fragile or brittle to break or shatter when struck with shot or similar projectiles. This body terminates with a marginal rim, B, bent inwardly so as to afford a concave chamber or annular channel of any appropriate degree of curvature, an intermediate member, D, serving to join said body and rim. Furthermore, this intermediate member is curved reversely with reference to the rim, thereby preventing the formation of an angle at the junction of the body with said rim and causing the pigeon to fly with less resistance against the air.

Projecting laterally from the exterior of rim B is a lug or tongue, C, which lug may be separate from the target, or it may be integral therewith. This lug or tongue is adapted to

be grasped by the jaw or clamp of the trap or sender and then projected into the air. The bird, when thrown from the trap, receives a very rapid rotation, owing to the weight of rim B, which axial motion of the target causes the air to be thrown outward and moderately compressed or chambered within the concavity or annular channel of said rim. Consequently the weight of the rim coacts with the compressed air within the same to give stability to the target and prevent it canting over on either side, while the convex exterior of the device causes it to sail or skim through the air with the utmost facility. Having completed its flight, the target descends gradually, provided it has not been struck by the sportsman, on the principle of a parachute, and for the further reasons stated in the preceding paragraph.

While I have described the target as composed of a fragile material, the invention is not to be limited to this or any other substance, as the present construction enables the device to be readily spun up from a suitable metallic blank, which metallic target would be especially desirable in some cases. Finally, the reverse curve D joining the rim to the body is not to be considered as an essential feature of the target, and may be omitted, if desired, as all the advantages of the invention will be attained by any target having an approximately concave body provided with an inwardly-turned rim or air-chambering receptacle.

I claim as my invention—

1. A flying target concave in general form, as at A, but having the edge or rim turned in at B to insure a rapid and stable axial rotation when thrown in the inverted position herein described, whereby a gradual descent of said target is caused by the imprisonment of air within its concavity, substantially as set forth. 90

2. A flying target composed of a fragile material that will readily shatter or break when struck with shot, said target being concave in general contour, but having its edge or rim turned in at B, to insure a rapid and stable axial rotation when thrown in the inverted position herein described, whereby a gradual descent of the target is caused by the imprisonment of air within its concavity, substantially as set forth. 95

3. A flying target concave in general form, as at A, but having the edge or rim turned in at B, to insure a rapid and stable axial rotation when thrown in the inverted position herein described, said rim being provided with a peripheral projection, C, for the purpose stated.
4. A flying target consisting of a concave body, A, united to the inturned rim B by an intermediate member, D, which latter is curved 10 reversely with reference to said rim, for the purpose herein described.

5. A flying target consisting of the body A D, having an inturned rim, B, which latter is provided with a projecting lug or tongue, C, for the purpose described.

In testimony whereof I affix my signature in presence of two witnesses.

GEORGE LIGOWSKY.
